UNITED STATES PATENT OFFICE.

AUGUST KOENIG, OF LOWELL, MASSACHUSETTS, ASSIGNOR, BY MESNE ASSIGNMENTS, TO THE LAMSON COMPANY, OF BOSTON, MASSACHUSETTS, A CORPORATION OF MASSACHUSETTS.

CARRIER-DIVERTING DEVICE FOR CARRIER-DISPATCH SYSTEMS.

Application filed March 8, 1921. Serial No. 450,552.

To all whom it may concern:

Be it known that I, AUGUST KOENIG, a citizen of the United States of America, and resident of Lowell, in the county of Middle-

sex and State of Massachusetts, have invented new and useful Improvements in Carrier-Diverting Devices for Carrier-Dispatch Systems, of which the following is a specification.

10 This invention relates to carrier dispatch systems, and more particularly to means useful in such systems for diverting carriers, and especially carriers arriving at a central station, from their normal course 15 of movement. While the present invention is applicable to such systems generally, the embodiment selected for illustration herein has been designed with particular reference to its application to apparatus such as dis- 20 closed in the patent to Whittier, No. 1,365,- 428, January 11, 1921.

The system of dealing with carriers and the devices illustrated in the said patent are highly effective under most circumstances 25 for the purpose intended and one object of the present invention is to increase the flexibility, under certain conditions of use, of the delivery of carriers from various sources to the various operators in such a system. As 30 illustrative of such a condition it may be noted, by reference to the aforesaid patent that upon the cashier's side of the central station desk, the carrier delivery chutes are so directed that those carriers arriving 35 through the tubes at terminals directly in front of any attendant will be delivered to another attendant to her right. Under ordinary circumstances this is desirable, but under some conditions of use, as for ex- 40 ample during a special sale in one department only of the store, that portion of the bank of incoming tubes directly in front of an attendant may be suddenly called upon to deliver a very large number of carriers 45 although the number of carriers arriving at their other portions of the bank may be normal or less than normal. Under such circumstances it is manifestly desirable to distribute the abnormal flow of in-

50 coming carriers more widely than can be done with the arrangement shown in the

patent, wherein, although proper distribution may be made to any attendant to the right of that part of the bank of incoming tubes in which carriers are arriving in great 55 numbers, it is not provided to divert any of such carriers to the attendant immediately in front of such tubes. Moreover, in any such system if an attendant is temporarily absent from her place, it is desirable to be 60 able to distribute her share of the work to others at her right or left, or in the entire absence of one attendant to deliver all of her share of the incoming carriers to the 65 attendant to the left, if the nature of the business warrants such arrangement.

The principal object of the present invention is to facilitate and make more flexible the distribution of necessary carriers to the various attendants under circumstances, 70 such for example as those above pointed out, or which may usually or occasionally arise in the course of business. Further objects of the invention are to provide suitable means whereby to aid in reaching the de- 75 sired results and more particularly, to provide manually actuatable carrier-diverting means of simple and durable type and such as may be readily operated without appreciable effort or loss of time on the part of 80 the attendant.

Preferred means for attaining the above objects may comprise delivery chutes at an angle to the length of the central station desk, and carrier diverting means at the entrance of the chutes, together with a movable deflector adjacent the delivery end of the chute whereby at will to cause the carriers to move to the right or left of the chute 85 as they emerge therefrom.

A preferred embodiment of means for carrying into effect the above objects is disclosed in the accompanying drawings, in which,—

Figure 1 is a fragmentary plan view of 95 the cashier's side of a central station desk, illustrating the devices of the present invention applied thereto;

Figure 2 is a vertical cross section of that portion of the desk illustrated in Fig. 1;

Figure 3 is a cross section to enlarged scale, and taken on a line such as 3—3 (Fig.

1) looking in the direction of the arrows, and illustrating one of the carrier diverting devices employed; and

5 Figure 4 is a fragmentary cross section to larger scale, taken on the line 4-4 of Fig. 2, and illustrating the means for retaining a carrier diverting gate in adjusted position.

10 The central station apparatus shown is such as is disclosed in the said patent to Whittier 1,365,428, January 11, 1921, above referred to. In the present drawings the incoming tubes are shown as having divided terminal portions forming the series 1^a, 1^b, 15 for the delivery of carriers for cash and charge authorization slips respectively. These tubes preferably terminate in momentum absorbing devices of usual form such as are shown at 3. Outgoing tubes 2 may be 20 arranged in one or more banks at the end of the series of incoming tubes as in the said patented apparatus.

25 The carriers received in the respective tubes in series 1^a are delivered upon a longitudinally arranged endless belt 4. This belt 4 may be mounted upon rollers as 5 to one or more of which motion is imparted by means of a belt 6, driven by an electric or other motor 17 of any ordinary form. 30 Preferably the belt 4 is arranged within a longitudinal channel or chamber 8 formed by the opposite walls 9, 10, of the desk-like structure upon the opposite sides of which the attendant's stations are disposed. As 35 illustrated in Fig. 2, the desk structure upon the cashier's side of the desk may comprise the shelf-like member 11 supported as by means of the member 12, it being understood that a generally similar shelf-like 40 member extends upon the opposite side of the desk and is there similarly supported.

45 In Fig. 1 attendants' stations are indicated at 13, 13^a and in Fig. 2 a suitable foot rest 14 is indicated for the use of the attendants. Upon the opposite side of the desk the terminals of the tubes 1^b may deliver their carriers upon a traveling belt such as 15 mounted upon rollers 16 and which may be driven in any suitable manner from the motor 17.

50 At points intermediate the several attendants' stations, the wall 10 of the channel 8 is provided with openings such as 18 from which lead inclined preferably tapering chutes 20. The chutes 20 comprise side walls 21, 22, and a bottom wall 23. At the receiving end of such chutes the wall 21 is curved outwardly through substantially a quadrant of arc as indicated at 24, thus terminating at 25 in a flange substantially parallel with the wall 10 to which it may be secured by screws or in any other suitable manner. At the terminal end of the wall 22 is provided an outstanding flange 26 55 whereby the chute may also be secured to

the wall 10. A bracket 27 is provided for supporting the lower end of the chute 20 upon the desk member 11.

For diverting carriers from belt 4 into and for closing the openings at the receiving ends of the chutes 20, at will, pivotally supported gate members 28 or 28^a are provided. Each such gate member is pivoted as at a point 29 adjacent the end of the wall 22 of a chute. These gates as herein shown are provided with concave front walls 30 and convex rear walls 31 and thus present smoothly curved surfaces for contact with the moving carriers whether in open or closed position. Secured to the curved portion of the wall 21 is arranged a buffer member 32 formed of felt or other suitable material for cushioning the impact of the free edge of the gate member when the latter is brought to closed position. A handle 34 is fixedly secured to the gate member 28 adjacent the pivotal edge thereof whereby the gate may readily be moved from open to closed position by the operator without necessitating her arising from her seat, and suitable means are provided for holding the gate open or closed.

90 The pivotal edge of the gate, for instance, is provided with a substantially radial socket opening 35 in which is suitably mounted a sleeve 36 the outer end of which is somewhat constricted as indicated at 37. Such constricted end serves to retain a ball 38 seated within the sleeve and resting upon a coil spring 39 within the sleeve. Projecting rearwardly from the flange 26 of the chute is a boss 40 having secured thereto a hardened wear-plate 41. This wear-plate presents oppositely inclined surfaces 42, 43, for wiping engagement with the ball 38. 100 As thus arranged, the ball and spring in cooperation with the wear-plate serve as resilient means for holding the gate in open or closed position.

105 The chutes 20 deliver the carriers end-on toward the edge board 50 of the desk. The described construction adapts the chutes and their gates to be separately assembled so that they may be metallic structures adapted to be installed anywhere along a conveyor such as 4, by attaching the flanges 25 and 26 to the conveyor trough.

110 Mounted upon the desk top 11 and in substantial alignment with each of the chutes 20 are carrier controllers comprising the receiving members 44. The members 44 are preferably formed of pressed metal of truncated triangular form and provided with suitable means such as the lugs 44^a 115 for attaching them to the desk. These receiving members comprise oppositely inclined surfaces 45, 46, with an interposed grooved surface 47, the latter forming an open trough or chute having a shallow channel arranged in substantial alignment with 120 125 130

the axis of the chute 20 and having its bottom substantially horizontal. Pivotally secured to the opposite ends of the support 44 are bracket arms 52 which serve to support a plate 53. Upon the outer surface of this plate 53 is attached a rib member 54 having sockets in its opposite ends for the reception of buffer members 55, 56, respectively. From the inner surface of the plate 53 and adjacent its edges extend fins 57, 58, such fins upon their inner edges being provided with cam surfaces as 59. A carrier moving endwise in groove 47 is forced laterally out of the groove by one of these cam edges, and caused to roll down the slope 45 or the slope 46, depending on the position of plate 53. The pivotal arrangement of the plate 53 is such that it may be swung in an arc about the pivotal point 51 of the brackets 52 and substantially about the axis of the channel 47. In Fig. 3, the plate 53 has been shown in dotted lines at 53^a as having been swung to the right of the support.

As will be noted from inspection of Fig. 1, the several chutes 20 may deliver the carriers endwise at substantially right angles to the path of movement of the carriers traveling along upon the belt 4. In the orderly operation of the device all carriers arriving through the tubes 1^a are deposited upon the belt 4 and are thus moved to the right in a substantially straight path extending longitudinally of the cashier's desk. If all of the gate members 28, 28^a, etc., corresponding to attendants' stations 13, 13^a are open as indicated at the right-hand side of Fig. 1, all carriers arriving through tubes 1^a intermediate such opened gates as 28, 28^a, for example will be diverted by the gate 28^a into the corresponding chute and will thus be delivered at the right-hand side of the operator at the station 13^a. Similarly, carriers arriving through tubes 1^a to the left of the gate 28 and not diverted by opened gates further to the left thereof, will be caused to pass through the chute immediately to the right of the operator at station 13. If in such case no devices such as the controllers comprising the supports 44 were placed at the ends of the respective chutes the carriers would be delivered promiscuously upon the upper surface of the desk at points immediately to the right of each of the attendants but by the employment of the controlling devices above described, it is possible to determine as to whether such carriers emerging from the ends of the chutes shall be delivered to operators to the right or left of the respective chutes.

By positioning the member 53 in the full or dotted line positions, Fig. 3, the arriving carriers from any chute will be caused to roll off the member 44 to the right or the left respectively, and so come into reach in

the order of their receipt, of the attendant at the right or at the left of the chute. An attendant leaving duty may thus at will, and without compulsion, arrange for delivering her share of the traffic to the attendant 70 at her left, or, by closing the gate 28, deliver her share to the attendant at her right.

By the provision of the controlling gates, as at 28, 28^a, together with the directing devices placed at the delivery ends of the 75 chutes, it is possible to secure a very flexible control of the delivery of carriers to the various attendants, thus greatly decreasing the probability of congestion at any attendant's station and facilitating the work of 80 making change and the returning of the carriers to their starting point.

Having thus described the invention and the preferred embodiment of the same, what I claim and desire to secure by United 85 States Letters Patent of the United States is:

1. A carrier dispatch central station comprising means for conveying carriers in a stream extending in a substantially straight 90 path, a chute arranged at an angle to said path, a normally inoperative gate member associated with said chute and movable across said path whereby to divert carriers into said chute, and carrier controlling 95 means at the delivery end of the chute comprising a support for receiving a carrier, and manually adjustable means for rolling a carrier from said support in one or the other direction. 100

2. In combination in a central station for carrier dispatch systems having therein means for moving a plurality of carriers in a longitudinally extending stream, a discharge chute arranged substantially at right 105 angles to the direction of said stream for receiving and guiding carriers endwise therefrom, means for directing carriers into the chute, and means associated with the terminal end of said chute whereby to roll the 110 carriers laterally to one or the other side of the axis of such chute.

3. A carrier controller for use with the delivery chute of a carrier dispatch system comprising an open and substantially horizontal trough constructed and arranged to form a substantial continuation of the bottom of the chute and aligned therewith, said receiving trough having a laterally and downwardly inclined surface, and a deflector for laterally deflecting a carrier moving along such receiving portion onto said inclined surface, said deflector being pivoted to turn about on an axis substantially parallel to that of the trough. 115

4. A carrier controller for use in carrier dispatch systems comprising an open chute providing a shallow substantially horizontal channel to receive a moving carrier, a surface extending laterally from said chute, 120

and means extending longitudinally of said chute for deflecting a carrier moving lengthwise of said channel whereby to cause it to diverge from the channel and engage and 5 roll over said surface.

5. A carrier controller for use in carrier dispatch systems comprising an elongate open guideway providing a shallow channel, a surface extending downwardly and laterally from an edge of said channel, and cam means for deflecting a carrier moving along 10 said channel whereby to cause it to move down said surface.

6. A carrier controller having a carrier 15 receiving portion comprising a surface with a shallow groove therein, surfaces extending laterally and downwardly from opposite edges of said groove, and movable means constructed and arranged alternatively to 20 deflect a carrier moving along said groove into engagement with one or the other of said surfaces.

7. A carrier controller comprising a carrier receiving support having a longitudinal guideway, a plate mounted to swing in 25 an arcuate path to either side of said guideway, stop means for supporting said plate when at either end of its path of movement, and a longitudinally extending cam fin projecting from said plate and normally lying 30 substantially in a horizontal plane, and adapted to cause a carrier moving in the guideway to be moved therefrom laterally.

8. In a carrier dispatch system in combination a carrier controller comprising a carrier receiving support having oppositely and downwardly inclined faces and a shallow groove for the carriers between the adjacent edges of said faces, and a cam-carrying member movable to one side or the other 40 of the axis of said groove.

Signed by me at Lowell Mass. this 4th day of March 1921.

AUGUST KOENIG.
